US00D928436S

(12) **United States Design Patent** (10) Patent No.: **US D928,436 S**
(45) Date of Patent: **** Aug. 17, 2021**

(54) **TRAY FOR A SURFACE CLEANING APPARATUS**

(71) Applicant: **BISSELL Inc.**, Grand Rapids, MI (US)

(72) Inventor: **Mackenzie L. Knapp**, Saranac, MI (US)

(73) Assignee: **BISSELL Inc.**, Grand Rapids, MI (US)

(**) Term: **15 Years**

(21) Appl. No.: **29/774,526**

(22) Filed: **Mar. 17, 2021**

Related U.S. Application Data

(62) Division of application No. 29/685,245, filed on Mar. 27, 2019, now Pat. No. Des. 923,891.
